HARRY B. MARSH, OF EVANSVILLE, INDIANA.

TOOL HANDLE.

Application filed August 23, 1926. Serial No. 130,881.

This invention relates to D-handles for shovels and the like.

The chief object of the invention is to provide a D-handle of wood and metal, preferably steel, which is not only adapted to take the loads and shocks to be sustained in use but will fit the hand in all positions in such fashion that it will give the greatest comfort with the least fatigue and which will have the proper "balance," and which furthermore will have its parts so arranged that the metallic portions are shielded preventing rusting and wood decay.

The chief feature of the invention consists in the accomplishment of the foregoing object by the utilization of a combination wood and steel handle which has a cantilever action when subjected to strain and which has its parts so arranged together that the resultant handle has all the necessary strength, balance and comfort of the old wooden D-handle.

The full nature of the invention will be understood from the accompanying drawings and the following description and claims:

In the drawings Fig. 1 is an elevational view with a part shown in quartered and longitudinal section. Fig. 2 is a longitudinal sectional view taken on line 2—2 of Fig. 1 and in the direction of the arrows. Fig. 3 is a top plan view of the ferrule.

In the drawings 10 indicates the stale of a fork or shovel or the like which is reduced at 11 and is further reduced at 12 and includes a rounded head 13. A ferrule having the rounded or curved cover portion 14 and peripheral flange portion 15 receivable by the reduced portion 12 is provided with a pair of upstanding projections or lugs 16 which are centrally positioned with respect to the resultant D-handle, as shown in Fig. 2. The ferrule is wedgingly received by the end of the stale.

The grip 17 is substantially circular in section throughout its length but is slightly curved or arcuate as shown in Figs. 1 and 2. Said grip includes a central bolt opening 18 extending therethrough and each end of the grip is reduced annularly as at 19 and is further provided with a transverse slot 20 which, just beneath the intersection with the opening 18, is extended inwardly and angularly as at 21.

A substantially U-shaped cover 22 is pro-

vided on its opposite parallel edges with a U-shaped groove 23 and said U-shaped cover is also arcuate in outline as indicated at 24. Said U-shaped cover bears upon the cap portion of the ferrule and is welded to the lugs or projecting portions 16 of said ferrule. The upper ends of the U-shaped cover are identical but oppositely positioned and each includes an outwardly and upwardly inclined portion 25 and a parallel extension 26, the latter being apertured to receive bolt 27. The strap portion 26 is receivable by the groove 20 and the wedging portion 25 is receivable by the inclined portion 21 of said groove. The U-shaped member 22 thus forms the inside of the D-portion of the handle. The exterior or body portion of the D-handle comprises a yoke forming member, which includes a semicircular arm portion 30 apertured at 31 to register with the opening 32 receiving the rivet 33, whereby the body of the handle is anchored to the stale 10 and in D-formation with the semi-circular portions 30 embracing the reduced portion 11 of said stale. Each fork extension of the yoke is substantially U-shaped in cross section throughout its length and extends outwardly and upwardly, the depth of the U decreasing toward the free ends. The upper opposite edges of the yoke, herein indicated by the numeral 34, are receivable by the groove 23 substantially throughout the curvature and thus the cover 22 covers the trough formed by said U-shaped portions, and also serves as a retainer and moisture protector.

Each upper free end 35 is apertured for registration with the aperture of the strap and the opening in the grip so that the rivet 27 will extend through all of the foregoing and rigidly anchor the aforesaid in unitary arrangement. When thus anchored the grip exerts a wedging action on the inclined portion 25 and causes the cover 22 to wedgingly engage or bear upon the upper edges of the U-shaped body portion of the handle. The upper end of each of said U-shaped body members is formed into a substantially circular cup 36 which is receivable by the reduced grooved end 19 of the grip 17. The associated relationship, therefore, of the several parts is entirely interlocking and the several edges are protected. The resultant construction consists of a combination steel and wood handle having substantially the same weight and balance as the old D-

handle and arranged so that it will give the greatest comfort with the least fatigue to the user thereof.

When downward pressure is applied to point "B", the tendency for said rivet and associated parts is to swing in an arc from a center at the bearing cap, but this movement is resisted by the rigidity of the yoke members forming the body which are riveted 10 to the stale and locked to the cover 22 throughout their length by the U-shaped seams 23. Any tendency of the U-shaped cover towards movement from the central plane is resisted by the engagement of said cover with the upper edges 34 of the yoke or body, said resistance being obtained through the envelopment of the end of the stale and through the anchorage thereto by rivet 32.

When a side thrust is applied at point 20 "B", on the handle it acts as a cantilever for this pressure tends to thrust one arm of the cover 22 anchored to the rivet 27 down against the ferrule supported by the end of the handle or stale. Movement is resisted 25 by the welded connection therewith and thus the cover is under compression and the same tends to force outwardly that portion adjacent the anchorage at rivet 27. Such tendency is prevented by the yoke or body which 30 is subjected to a tension force, thus affecting or completing cantilever action. Simultaneously therewith in the lower half of the D-handle the stresses are reversed in the cover and the yoke and also each of the yoke and 35 cover portions adjacent thereto support or divide the load.

The cover 22 and the ferrule take the shock when the shovel is used and as the yokes are in one piece there is no separation 40 strain at the median line of the enclosing portion surrounding the end of the stale, which separation is a common weakness of other metallic yokes made in two pieces or with a similar median parting line. The 45 present arrangement in addition to eliminating this weakness, also includes sufficient spring in the metal by reason of the shape of the parts to obtain the desired flexibility in this type of handle.

It will be apparent from the foregoing 50 description relative to the anchorage of the free ends of the cover and the yoke that the cooperating relationship is such with the grip handle that a wedging and non-rotative mounting is obtained. The particular arrangement of the cover 22 is such that it 55 gives greater clearance in the lower part of the eye of the D and also as constructed gives greater strength to the base of the D and 60 gives resiliency to that portion of the cover mounting the grip where the same is desired.

The invention claimed is:

1. In a D-handle, the combination of a 65 yoke end including a grip receiving socket

and inclined wedge portion in longitudinal alignment therewith and a grip having an end engageable by the wedge portion and receivable by the socket.

2. In a D-handle, the combination of a 70 trough shaped yoke, and a substantially U-shaped cover therefor, said cover having a groove at opposite sides for receiving the yoke edges.

3. A device as defined by claim 2, characterized by the cover being substantially 75 arcuate in transverse section intermediate its groove.

4. A device as defined by claim 2, characterized by the addition of a stale ferrule 80 rigidly united to said cover.

5. In a D-handle, the combination of a trough-shaped sheet metal yoke, each arm terminating in a grip receiving socket, a substantially U-shaped cover for said trough, 85 the ends thereof extending into said sockets, and a grip receivable by the sockets and having complementary portions engageable by the cover ends for preventing grip rotation. 90

6. A device as defined by claim 5, characterized by the different ends extending angularly in the socket and the grip ends including an angular recess for yielding engagement therebetween. 95

7. A device as defined by claim 5, characterized by the addition of a stale ferrule for receiving the end of a stale and enclosed by a yoke and cover and connected thereto. 100

8. In a D-handle, the combination of a substantially hollow sheet metal D having a tubular stale receiving end, and a stale receiving ferrule in alignment with said tubular end, for receiving the stale end and enclosed by the hollow D and supported 105 thereby.

9. In a D-handle, the combination with a grip and a stale, of a yoke secured at its bight portion to the stale removed from the end thereof, a cover of substantially yoke form cooperating with the first mentioned yoke, a member carried by the end of the stale, the bight portion of said cover rigidly secured to said member, the ends of the yoke and cover member positioned close together, and means connecting said ends with the grip. 110

10. In a D-handle, the combination with a grip and a stale, of a yoke secured at its bight portion to the stale, a cover of substantially yoke form cooperating with the first mentioned yoke, a cup member at the bight portion of said cover engaging the stale and holding the latter against lateral displacement, and means for securing the ends of said yoke and cover to said grip. 120

In witness whereof, I have hereunto affixed my signature.

HARRY B. MARSH.
